UNITED STATES PATENT OFFICE.

LAWRENCE L. NEEBE, OF WOODBURY, NEW JERSEY, ASSIGNOR TO THE BALDWIN LOCOMOTIVE WORKS, OF PHILADELPHIA, PENNSYLVANIA, A CORPORATION OF PENNSYLVANIA.

FIRE-BOX FOUNDATION RING.

Application filed January 29, 1926. Serial No. 34,661.

The object of my invention is to make a boiler fire box foundation ring of a single casting, having side members, end members, and a longitudinal central member, which, together with the side members, support the grates of the fire box.

The invention also relates to means for securing the waist of the boiler to the ring, and to means for carrying the fire wall which separates the fire chamber from the combustion chamber.

The foundation ring is designed for a locomotive boiler, but it will be understood that the invention can be used in connection with other boilers of the locomotive type.

In the accompanying drawings:

Fig. 1 is a plan view of my improved fire box foundation ring;

Fig. 2 is a side view partly in section on the line 2—2, Fig. 1;

Fig. 3 is a longitudinal section on the line 3—3, Fig. 1;

Fig. 4 is an end view of the forward end of the ring;

Fig. 5 is an end view showing the rear end of the ring;

Fig. 6 is a transverse section on the line 6—6, Fig. 1;

Fig. 7 is a transverse sectional view on the line 7—7, Fig. 1;

Fig. 8 is an enlarged sectional view on the line 8—8, Fig. 1.

Fig. 9 is a longitudinal sectional view of part of a locomotive fire-box illustrating my invention.

The foundation ring is the bottom portion of the fire box of a locomotive boiler, and is made hollow so that it acts as the lowest circulating chamber and also as the muddrum. The ring is rectangular, as clearly shown in Fig. 1, and has tubular longitudinal side members 1—1, a tubular front member 2, and a tubular rear member 3. The end members are connected to the side members so that there will be a free circulation of water in the ring.

At the center of the ring is a longitudinal hollow bar 4, which extends the full length of the ring and communicates with the tubular end members 2 and 3, as clearly shown in Figs. 1 and 3. The longitudinal member acts as a central support for the grate-bars, which are carried by the side members 1 and the central member 4.

A hollow transverse member 5 extends

from one side member to the other and intersects the central member 4, and also communicates with the side members, so that there is free circulation of water throughout all of the members. This transverse member 5 is at the rear of the combustion chamber and acts as a support for the fire-wall *a*, and also has openings 6 for the supporting tubes *b*, which extend to the upper portion of the boiler within the fire-box and carry the inclined fire-brick deflector *c*. In the space in front of the fire-brick arch supported by the transverse member 5 is a combustion chamber *d*, and the open spaces in the ring are closed by plates 7, Fig. 1.

The central longitudinal member 4 has a series of vertical tubes 8, which extend through the section and are open at top and bottom, being flanged over the upper and lower walls of the member 4, as clearly shown in Fig. 3. These tubes supply air to the fire directly over the central bar, thus preventing the burning out of the central section of the grate.

The forward end of the ring is made as shown in Fig. 4, and has flanges 9 and 10 by which it is secured to the waist of the boiler, and openings 11 which communicate with the lower portion of the boiler through pipes, so that a circulation is maintained. Depending from the transverse member 5 and the rear member 3 are flanges 5^a and 3^a, respectively, to which waist-sheets are attached.

In each of the side longitudinal members 1—1 is a series of holes 12 to which vertical side tubes of the fire box are coupled. These tubes extend to an overhead structure in the fire-box, as fully disclosed in my pending application filed on the 23rd day of October, 1926, Serial No. 143,777.

The ring has a vertical flange 13 on each side to which the fire-box cover plates are attached, and has a flange at the rear end as at 14 for attachment to a rear cover plate.

Directly under the openings 12 in the side members 1—1 and back member 3 and also under the openings 6 in the transverse member 5 are plug openings 15, which when the plugs are removed, allow a tool to be inserted by which access can be had to the tubes which are coupled to the ring.

16 are blow-off openings at each side of the ring opposite the transverse member 5. There are openings 17 at each side of the structure in line with the channel at the forward end of

the ring, and openings 18 at each side in line with the rear end 3. These openings 17 and 18 are closed by plugs. By removing the plugs, access can be had to the channels within the ring for washing purposes.

The entire ring is made of a single casting and has comparatively few finished parts. This ring supports the entire fire box structure, including the fire-brick, as well as the 10 side tubes and the usual casing enclosing the fire-chamber.

I claim:

1. A fire-box foundation ring made as an integral casting, and having longitudinal hollow side members; hollow end members; a hollow longitudinal central member communicating with the end members; and a transverse hollow member intersecting the central longitudinal member and communicating with the side members.

2. A foundation ring for a fire-box having a fire-wall, said ring being made in a single casting, and having hollow longitudinal side members; hollow end members; a longitudinal hollow central member; and a hollow transverse member intersecting the central member, the said transverse member being on a line with the fire-wall of the fire-box and having openings for tubes, and the side members having openings in the upper surface for vertical tubes located at the sides of the fire-box structure.

3. A foundation ring for a fire-box having a fire-wall, said ring being made in a single casting, and having hollow longitudinal side members; hollow end members; a longitudinal hollow central member; and a hollow

transverse member intersecting the central member, the said transverse member being on a line with the fire-wall of the fire-box 40 and having openings for tubes, and the side members having openings in the upper surface for vertical tubes, located at the sides of the fire-box structure, the central longitudinal member having a series of tubes extending vertically through the said member and open at top and bottom to admit air to the fire over the central member.

4. A hollow rectangular fire-box foundation ring having hollow end members communicating with hollow side members; a longitudinal hollow member extending the full length of the ring and communicating with the end members; a transverse member intersecting the central member and communicating with the side members; and plates covering the openings between the front end member and the transverse member and between the longitudinal end member and each side member.

5. The combination in a rectangular fire-box foundation ring, having two hollow longitudinal side members; hollow end members communicating with the side members; a longitudinal central member; and a transverse member intersecting the central member and communicating with the side members, the forward end, back end and transverse members of the ring having flanges by which the waist-sheets of the locomotive are attached to the said ring, and having vertical flanges around the sides and back to which cover and supporting plates may be attached.

LAWRENCE L. NEEBE.
